UNITED STATES PATENT OFFICE.

FREDERICK D. BIGHAM, OF BALTIMORE, MARYLAND.

AUTOMATIC TRAIN-STOPPING MECHANISM.

1,175,043.

Specification of Letters Patent. Patented Mar. 14, 1916.

Application filed February 9, 1915. Serial No. 7,158.

To all whom it may concern:

Be it known that I, FREDERICK D. BIGHAM, a citizen of the United States, and a resident of Baltimore, in the State of Maryland, have made certain new and useful Improvements in Automatic Train-Stopping Mechanism, of which the following is a specification.

My invention relates to improvements in train stopping mechanism for railway safety systems, and consists in the constructions, combinations, and arrangements herein shown, described and claimed.

An object of my invention is to provide means by which the air pressure from the main reservoir may be caused to automatically close the throttle and subsequently open the train line pipe to the atmosphere, so as to shut off the steam and set the air brakes and so stop the train.

A further object of my invention is to provide means whereby the number of times the throttle is closed by the air pressure is registered.

25 A further object of my invention is to allow the throttle to be closed manually without causing the air brakes to be applied or the operation registered.

Other objects and advantages will appear 30 in the following specifications and the novel features of the device will be particularly pointed out in the appended claims.

35 My invention is illustrated in the accompanying drawings forming part of this application in which—

Figure 1 is a top view of the throttle lever, certain other parts being shown in section and Fig. 2 is a section through the controlling means for the escape of the air from the 40 train line pipe.

The apparatus herein described is designed to be used in a safety system in which means is brought into play for admitting the air pressure from the train air reservoir (not shown) to the apparatus which forms the subject of this application, as the train passes over a given point. The particular means by which this is done forms no part of the present invention, since it is obvious 45 that the throttle closing mechanism and the means for operating the escape valve on the train line pipe might be operated by any mechanism for turning on the air.

In carrying out my invention I provide a 50 pipe A¹ leading from the source of compressed air and controlled by any suitable

means for admitting the air pressure from the air reservoir. The pipe A¹ is connected at the other end to a cylinder A² in which is a piston A³. The opposite end of the cylinder A¹ is open and is provided with a shoulder B¹. The cylinder A¹ is secured to a frame F which in turn is secured to any suitable part of the locomotive such as the boiler front B³ by means of the brackets A⁴ 60 and C⁴. Pivotal secured to the frame F by means of the pivot pin B² is the throttle lever L. This lever is provided with a slot C² through the body portion of which the pin C³ extends which connects the throttle 65 lever with the throttle valve stem B⁴.

One end of the throttle lever L is provided with a handle D⁸ having an unlocking member D⁷ which is connected to a spring-actuated locking device G¹ arranged 70 to engage a locking segment D¹ carried by the frame F. The locking member G¹ is provided with guide pins D⁶ arranged to move in a slot G³ in the throttle lever L. A plate G² is carried by the pins D⁶ and is 75 provided with a rounded end.

The throttle lever L is provided with an extension E⁵ so that the lever L and the extension E⁵ form in fact a bell-crank lever arrangement. The extension E⁵ is provided 80 with a pin E⁶ the body portion of which passes through the slot E⁴ in the plate E³ which is pivotally connected by a rod E² to the piston A³. The plate E³ is pivotally 85 connected at E⁷ to a bar E⁸ having a slot D² 90 through which the body portion of the pin D³ carried by the lever L extends. The end D⁴ of the bar E⁸ is arranged to engage the end D⁵ of the plate G² as will be hereinafter 95 explained. A spring C⁵ is secured to the throttle lever L and to the bar E⁸.

Connected to the cylinder A² is a pipe E¹ 100 which communicates with a cylinder H⁷ which is secured to any suitable part of the locomotive, preferably out of reach of the engineer. The cylinder H⁷ has placed therein a piston H⁹. Disposed in alignment with the cylinder H⁷ is a second cylinder or chamber J² which is connected by means of the pipe J⁴ to the main train pipe (not shown). A valve J⁵ is disposed within the cylinder 105 J² and controls the air passage J⁶. The opposite end of the air passage J⁶ is closed by a valve K¹ which together with the spring K³, the screw K⁵, the casing K⁴, the stem K⁶ 110 and the vent K² form in fact an adjustable spring safety or relief valve. The valve J⁵

is carried by the stem J^1 which extends through the cylinders J^2 and H^7 , and which is secured to the piston H^9 in the cylinder H^7 . On the opposite side of the piston H^9 5 is secured a stem H^5 which extends through the plug H^6 of the cylinder H^7 . Pivots secured at H^4 is a lever H^3 one end of which is disposed in the path of the stem H^5 the other end of the lever H^3 is arranged to engage the operating stem of the registering 10 device H^2 . Within the cylinder J^2 is a stop J^3 disposed in the path of the valve J^5 .

From the foregoing description of the device the operation is easily understood and 15 is as follows: As heretofore stated the air pressure is admitted through the pipe A^1 by an emergency apparatus carried by the train (not shown). The pipe A^1 being small in 20 size offers resistance to the passage of the air and so prevents the lever L from slamming into its closed position too suddenly. This being preferred to a regulating valve which might be closed and so render the 25 device ineffective.

When the air enters the cylinder A^2 the 30 piston A^3 is forced to the right in Fig. 1, thereby causing the rod E^2 and the plate E^3 to move in the same direction. This forces the bar E^8 forwardly until its end D^4 engages the end D^5 of the plate G^2 thereby 35 forcing the locking member G^1 out of engagement with the teeth of the locking segment D^1 . Further movement of the piston A^3 will now bring the end of the slot E^4 into 40 engagement with the pin E^6 , and this will swing the throttle lever L about on its pivot B^2 thereby moving the throttle valve stem B^4 so as to shut the throttle valve and close off the steam. When the piston A^3 reaches 45 the end of its stroke it is stopped by the shoulder B^1 in the cylinder A^2 . This prevents undue strain from being placed on the weaker parts of the device, and an adjustment is provided at C^1 to adjust the proper tension on the closed throttle valve when the piston A^3 is held firmly against the shoulder B^1 . As soon as the piston A^3 50 is forced by the air past the pipe E^1 air is admitted through the latter into the cylinder H^7 thereby causing the piston H^9 to be forced to the left in Fig. 2 against the tension of the spring H^8 . The stem H^5 engages the lever H^3 and this registers the fact that the throttle lever L has been automatically 55 moved into its closed position by air coming through the pipe A^1 . The movement of the piston H^9 also moves the rod J^1 which causes the valve J^5 to leave its seat and move to the left in Fig. 1 back against the stop J^3 thereby permitting the air in the train pipe J^4 to escape through the passage J^6 thus setting the air brakes. The air passing through 60 the passage J^6 raises the valve K^1 from its seat until the desired reduction of pressure has taken place in the train pipe J^4 then the 65

spring K^3 causes the valve K^1 to close, and so controls the strength with which the air brakes are applied. It will be seen that the throttle lever L may be used in the ordinary way manually, and placed in any desired 70 position by the engineer. The piston A^3 will then play idly in the cylinder A^2 while the spring H^8 together with the pressure on the valve J^5 holds the latter in its closed position, thereby preventing the escape of 75 air from the train pipe J^4 . The spring C^5 at the same time holding the bar E^8 from interfering with the locking arrangement. Therefore it is quite obvious that the throttle lever L may be used in the ordinary way 80 manually without causing the air brakes to be applied, or registering the operation. But when the throttle is closed automatically it registers the fact and causes the air brakes to be applied at any desired strength, 85 so stopping the train.

I claim—

1. In a train stopping mechanism, a cylinder, a piston therein, connections between said cylinder and a source of compressed air, a frame, a throttle lever pivotally mounted on said frame, a locking segment carried by said frame, a spring actuated locking member carried by said throttle lever and arranged to engage said locking segment, means connected to said piston for disengaging said locking member from said locking segment and for subsequently moving said throttle lever into its closed position, said last mentioned means comprising 100 a rod pivotally secured to said piston and having an integral slotted plate, a guide pin secured to a portion of said throttle lever and arranged to enter the slot in said slotted plate, a slotted bar pivotally secured to said slotted plate and arranged to engage the locking member carried by said throttle lever, guide means carried by said throttle lever and arranged to extend through the slot in said slotted bar. 110

2. In a train stopping mechanism, a cylinder, a piston therein, connections between said cylinder and a source of compressed air, a frame, a throttle lever pivotally mounted on said frame, a locking segment carried by said frame, a spring actuated locking member carried by said throttle lever and arranged to engage said locking segment, means connected to said piston for disengaging said locking member from said locking segment and for subsequently moving said throttle lever into its closed position, said last mentioned means comprising a rod pivotally secured to said piston and having an integral slotted plate, a guide pin secured to a portion of said throttle lever and arranged to enter the slot in said slotted plate, a slotted bar pivotally secured to said slotted plate and arranged to engage said locking member carried by said throttle lever. 120 125 130

lever, guide means carried by said throttle lever and arranged to extend through the slot in said slotted bar, and a spring connecting said slotted bar with said throttle lever.

3. In a train stopping mechanism, a cylinder, a piston therein, connections between said cylinder and a source of compressed air, a frame, a throttle lever pivotally mounted on said frame, a locking segment carried by said frame, a spring actuated locking member carried by said throttle lever and arranged to engage said locking segment, means connected to said piston for disengaging said locking member from said locking segment and for subsequently moving said throttle lever into its closed position, said last mentioned means comprising a rod pivotally secured to said piston and having an integral slotted plate, a guide pin secured to a portion of said throttle lever and arranged to enter the slot in said slotted plate, a slotted bar pivotally secured to said

slotted plate and arranged to engage said locking member carried by said throttle lever, guide means carried by said throttle lever and arranged to enter the slot in said slotted bar, and a spring connecting said slotted bar with said throttle lever, and means for subsequently causing the air brakes to be applied, said last mentioned means comprising a pipe connecting said cylinder with a second cylinder, said second cylinder having a piston therein, a piston rod connected at one end to the piston in second mentioned cylinder, the other end of said piston rod connected to a valve placed in an air tight valve chamber, said valve controlling a vent passage from the main train pipe to the atmosphere and acting independently of the engineer's valve for applying the air brakes.

FREDERICK D. BIGHAM.
